CLAIM

I claim the ornamental design for a raingutter sun shade for open animal shelter, as shown and described.

DESCRIPTION

FIG. 1 is a perspective view of a raingutter sun shade for open animal shelter;

FIG. 2 is a left side elevation view of the design of FIG. 1;

FIG. 3 is a right side elevation view of the design of FIG. 1;

FIG. 4 is a first end elevation view of the design of FIG. 1;

FIG. 5 is a second end elevation view of the design of FIG. 1;

FIG. 6 is a top view of the design of FIG. 1; and,

FIG. 7 is a bottom view of the design of FIG. 1.

The broken lines shown in the figures are for the purpose of illustrating environment only and form no part of the claimed design.
